(57) **CLAIM**

We claim the ornamental design for a monitor support, as shown and described.

DESCRIPTION

FIG. 1 is a front perspective view of a monitor support; FIG. 2 is a rear perspective view of the monitor support of FIG. 1; FIG. 3 is a bottom perspective view of the monitor support of FIG. 1; FIG. 4 is front view of the monitor support of FIG. 1; FIG. 5 is a rear view the monitor support of FIG. 1; FIG. 6 is a left side view of the monitor support of FIG. 1; FIG. 7 is a right side view of the monitor support of FIG. 1; FIG. 8 is a top view of the monitor support of FIG. 1; FIG. 9 is a bottom view of the monitor support of FIG. 1; FIG. 10 is a cross-sectional view along X-X of the monitor support of FIG. 4; FIG. 11 is a cross-sectional view along XI-XI of the monitor support of FIG. 7; FIG. 12 is a cross-sectional view along XII-XII of the monitor support of FIGS. 8; and, FIG. 13 is a cross-sectional view along XIII-XIII of the monitor support of FIG. 8. The evenly-spaced broken lines in FIGS. 1-10 illustrate portions of the monitor support that form no part of the claimed design. The dash-dot-dash broken lines in FIG. 3 illustrate the boundary of the claimed designs which forms no part thereof.

1 Claim, 10 Drawing Sheets
